MINING MACHINE UNDERCUTTER

John D. West, Manitowoc, Wis., assignor to Safeway Mining Machine Company, Chicago, Ill., a corporation of Delaware

Application June 29, 1949, Serial No. 102,103

14 Claims. (Cl. 262—9)

1 This invention relates to mining machines and particularly to an undercutting mechanism to cut a kerf across a portion of the working face of a vein of mineral material and means to facilitate breaking down material over said kerf.

It is desirable, in mining operations, to loosen and remove mineral material from its natural location as nearly continuously as possible and many attempts have heretofore been made to provide machines to cut and remove such material, particularly coal, without the necessity of undercutting, drilling, shooting, and removing the loosened material. In general, this invention relates to the type of machine adapted to loosen and remove coal or the like without the necessity of using explosives. The invention is directed particularly to means for cutting the horizontal kerf in the mineral working face in advance of breakdown means adapted to loosen the material above the kerf so cut. The present invention constitutes an improvement of the machine described and claimed in copending application Serial No. 25,015, filed May 4, 1948, in the name of George A. Merchant, now Patent No. 2,531,072. According to the disclosure in that application, the breaking down means consists of a plurality of picks orbitally movable in vertical planes to break down material above an undercut kerf. During the breaking down operation the machine tends to rise off the floor of the mine but the machine is so designed that a portion of the frame thereof engages a horizontal kerf, continuously cut in advance of the breaking down means, to prevent such rising. The present invention incorporates improvements therein in the undercutting and breaking down means and contemplates an improved conveyor mechanism for receiving broken down mineral and conveying it toward the rear of the machine.

The undercutting mechanism of the present invention comprises orbitally movable cutter heads movable in closed orbits in a horizontal plane adjacent the floor of the mine. These heads constitute the foremost portions of the machine and extend forwardly considerably in advance of the breaking down means. At least two such heads are provided and are mounted adjacent the sides of the machine so that their cutting movement takes place inwardly toward the center line of the machine. The improved hold-down means comprises a plate extending laterally across the machine and over portions of the undercutters and includes a rearwardly directed step over which mineral material is

2 adapted to extend to facilitate breaking by the downwardly movable breaking-down means herefore mentioned.

It is an object of this invention to provide an undercutter for a mining machine capable of cutting a continuous kerf extending transversely across the entire working face of the mineral material and of a slightly greater width than the transverse dimensions of the machine itself.

10 It is also an object of this invention to provide an undercutting mechanism adapted to move cut material from the kerf progressively inwardly and rearwardly of the machine to a conveyor.

15 It is another object of this invention to provide an undercutting mechanism incorporating pushing means to move material cut thereby toward a conveyor.

20 It is a still further object of this invention to provide an undercutting mechanism having hold-down means to prevent rising of a mining machine therein said hold-down means are of new and improved construction.

25 It is a further object of this invention to provide, in a mining machine of the type disclosed, auxiliary conveyor means to receive broken-down material and move the same rearwardly and inwardly toward a main conveyor.

Another object of the invention is to provide an undercutting mechanism wherein the drive means are completely enclosed and thus protected from dust and grit and wherein the working parts are compactly arranged and of unusual strength and ruggedness.

Additional objects and advantages will appear as the description proceeds in connection with the accompanying drawings wherein:

Fig. 1 is a side elevation view of a mining machine incorporating the present invention, parts of the machine being broken away.

40 Fig. 2 is a plan view of the undercutter shown in Fig. 1 and comprises that portion of the machine extending forwardly from the endless treads of the supporting carriage.

45 Figs. 3, 4 and 5 are plan views of one of the cutter heads, showing the same in various positions of movement about its orbital path, the top or hold-down plate being removed and portions of the frame being shown in section.

Fig. 6 is a vertical sectional view taken substantially along the line 6—6 of Fig. 4, and showing a portion of a conveyor.

Fig. 7 is a vertical sectional view taken substantially along the line 7—7 of Fig. 2 and showing the parts on an enlarged scale.

Fig. 8 is a sectional view taken substantially

along the line 8—8 of Fig. 2 and also showing the parts on an enlarged scale.

Fig. 9 is an enlarged sectional view taken substantially along the line 9—9 of Fig. 3.

Fig. 10 is a fragmentary sectional view taken along the line 10—10 of Fig. 2, and

Fig. 11 is a perspective view of a plurality of links of the auxiliary or apron conveyors, showing the manner in which the links are interengaged to form a substantially continuous conveyor surface.

The undercutting mechanism of the present invention is particularly adapted for use with a mining machine of the type disclosed in the above-identified copending application and is intended to replace all portions thereof extending forwardly of the endless treads shown therein. The main portion of the machine, comprising the carriage 2, conveyor 3, and breakdown mechanism 4 will not be described in detail since it is adequately disclosed in the copending application referred to. However, it will be stated that the main frame 6 of the machine supports an auxiliary frame 8 for pivotal movement about an axis 9. The auxiliary frame 8 in turn supports a shaft 10 having a plurality of eccentrics 11 mounted thereon. Each eccentric is engaged with a movable pick head 12 having a pair of groups of pick points 13 and 14 vertically spaced thereon and being guided at their rearmost ends by swinging links 16. Suitable drive means transmit power to the shaft 10 and cause it to rotate in such direction that the pick points 13 and 14 are caused to move forwardly and downwardly in engagement with the mineral face, then backwardly and upwardly to again move into engagement with the mineral and downwardly in breaking down movement. The movement of the pick points 13 and 14 may be described as orbital in that it follows a continuous closed path somewhat oval in shape.

The undercutting mechanism of the present invention is carried as a forward extension of the main frame 6 and includes a horizontally extending upper plate 60 engageable with the downwardly facing surface of the kerf cut by the mechanism. The plate 60 terminates in a transverse laterally extending terminal edge 20 positioned rearwardly of the undercutting means but forwardly of the lowermost position of the breaking down picks 14. It will thus be seen that as the machine advances into the mineral material, the plate 60 and step 20 will be in advance of the rearwardly extending portions 21 of the uncut mineral material. When the breaking down picks 14 move downwardly in a cutting cycle and approach the lowermost portion of their paths, the overhanging material 21 may be readily broken from the mineral face since the edge 20 will constitute somewhat of a fulcrum for the said material rearwardly of which it is unsupported.

Although shown in connection with the machine described in the identified copending application, it is to be understood that the undercutting mechanism of the present invention is not to be so limited but may be employed with other mining machines having means for breaking down material above an undercut kerf.

Referring now particularly to Figs. 2, 3—5 and 6, the forward portion of the main frame of the mining machine may comprise forwardly extending rigid frame members 22 (Figs. 2 and 6), a bottom plate 24 and a top or upper plate 26. A central conveyor chain 28 extends over a sprocket

29 mounted on a transverse shaft 30 (Fig. 6) and carries spaced conveyor flights 32 pivoted as at 33 to the chain 28. The flights 32 are spaced longitudinally of the chain and during operation of the conveyor the bottom flights move forwardly above the bottom plate 24, then upwardly over the sprockets 29 and rearwardly along the top of the upper plate 26. Material resting on the upper plate 26 will be engaged by the flights 32 and moved rearwardly of the machine to a suitable discharge position.

The shaft 30 has pairs of sprockets 34, outwardly of the sprocket 29 and about which apron conveyors 35 are trained. The apron conveyors 35 will be described in greater detail later.

The lowermost plate 24 of the main frame extends forwardly of the shaft 30 and its laterally outermost edge portions 38 (Fig. 4) extend forwardly a greater distance than the intermediate portion. Vertically arranged frame members 40, 42, 43 and 44 are welded or otherwise rigidly attached to the bottom plate 24 and form therebetween an elongated hollow housing 46. The members 42 terminate at their rearmost ends a short distance behind the forward edge 47 of the bottom plate 24 and transverse vertical members 48 are welded or otherwise rigidly attached to the bottom plate 24 and to the rearmost end of the member 42. The members 48 extend inwardly toward the longitudinal center line of the machine but terminate short of said center line adjacent the rearmost edge of a vertically extending plate member 50. Additional vertical members 51 further rigidify the structure and form continuations of the housings 46.

The undercutting means are supported by and driven through housings 52, which are reverse duplicates of each other and only one of which will be described in detail. Each housing 52 comprises upper and lower sections 53 and 54 (see Figs. 6 and 9) bolted or otherwise secured together to form a unitary hollow housing. Each of the housings 52 has a rearwardly extending arm 55 (Fig. 4) terminating in a bracket or pad 56 attached to the vertical frame member 42 as by cap screws 57 or in any other suitable manner. A coupling member 58 is bolted or otherwise rigidly attached to the inner face of the frame plate 43 and to a portion 59 of the housing 52. In this manner the housings 52 are rigidly and fixedly attached to the main frame of the machine at longitudinally spaced points, thus insuring efficient bracing and rigidity to withstand the stresses to which they are subject.

The vertical frame members defining the housings 46, and the forwardly extending side portions of the bottom plate 24 thus constitute forwardly extending portions of the main frame of the machine and define the lateral extremities of the machine. Extending transversely across the mining machine and across the tops of the forwardly extending housings 46 is the upper plate 60. This plate constitutes a closure for the tops of the housings 46 and defines the upper surface of that portion of the undercutter adapted to enter the kerf cut in the mineral face. A portion of the plate 60 defines the terminal edge 20, previously referred to, and as clearly shown in Fig. 2, that terminal edge extends transversely of the machine between the housings 46.

The upper sections 53 of the housings 52 are provided with inwardly extending projecting portions 62 (see also Fig. 9) terminating in attachment portions 63. The plate 60 has attached thereto on the under side thereof, a pair of bosses

64, laterally spaced on opposite sides of the longitudinal center line of the machine and vertically aligned with the portions 63 of the upper housing members 53. A bolt 65, or other suitable fastening means, passes through the member 63 and the bosses 64 to rigidly attach the extension 62 to the top plate 60. Thus, the housings 52 are rigidly attached to the main frame of the machine at three horizontally spaced points which results in an extremely rigid structure capable of withstanding the high stresses resulting from the operation of the undercutter.

A vertical brace 66 (see Figs. 2, 4 and 10), in the form of a flat plate-like structure arranged vertically, extends from the bottom plate 24 to the top plate 60 and constitutes additional bracing means for the said top plate. A reinforcing member 67 extends beneath the rearmost edge of the plate 60 to add strength thereto at the step or edge 20 and constitutes a bearing between the plate 60 and the brace 66. A second plate 68 extends across the machine and defines a surface somewhat below the top surface of the plate 60 immediately to the rear of the step 20. The plate 68 extends entirely across the machine and rearwardly to a terminal edge 69 spaced forwardly of the shaft 30 and the central conveyor driven thereby at its central portion. The end portions of the plate 68 extend rearwardly to the frame plates 46, which are closely adjacent the forward ends of the apron conveyors 35. The plate 68 is provided with a transverse edge-reinforcing member 70 at its central portion. The plate 68 also rests upon the brace 66 and may be rigidly attached thereto. As clearly shown in Fig. 10, the brace 66 is of limited fore and aft extent and is chamfered or bevelled at its forward edge to reduce the resistance to movement of mineral material therearound.

Suitable ribs 72 or other reinforcing means are attached to the under-surface of the plates 60 and 68 and extend from the bosses 64 inwardly and rearwardly to the brace 66.

The connecting member 58 (see Fig. 9) is of generally cylindrical configuration and hollow and is provided at its outermost end with a suitable seat for an anti-friction bearing 74. The mating sections of the housing 52 provide a seat for an inner anti-friction bearing 75. A shaft 76 is mounted for rotation in the bearing 75 and carries a bevel pinion 77 at its inner end, within the hollow interior of the housing 52. The outermost end of the shaft 76 is splined or otherwise formed to drivingly engage a sprocket 78. The sprocket 78 is within the housing 46, previously described and has a hub portion 79 extending into the connecting member 58. The hub 79 is rotatably supported by the bearing 74. If desired, the shaft 76 may be provided with a threaded end portion 80 and a nut 81 may be employed to hold the sprocket 78 in position on the shaft 76. Suitable dust sealing means 82 are preferably provided outwardly of the bearing 74 to prevent entry of dust or other foreign material into the interior of the housing 52.

Sprocket chains 84 (Fig. 2) are trained over the sprockets 78 and over sprockets 86, mounted on the ends of the transverse shaft 30 previously described. Thus the shafts 76 are connected to and driven by the shaft 30.

Referring again to Fig. 9, the upper and lower sections 53 and 54 of the housing 52 are provided with aligned openings defining seats for anti-friction bearings 88 and 89. The bearings 88 and 89 mount a hollow shaft 90 for rotation

on a vertical axis in the housing 52. The hollow shaft 90 is provided with a flange 91 to which a bevel gear 92 is riveted, bolted, or otherwise suitably attached. The bevel gear 92 is arranged to mesh with the bevel pinion 77 whereby rotation of the shaft 76 will cause the hollow shaft 90 to rotate about its axis. The shaft 90 terminates at its ends short of the outer surfaces of the housing 52 and is provided with internal keyways. A pair of cranks 94 have inwardly extending hubs 95 extending into the hollow shaft 90. The hubs 95 are suitably keyed to the shaft 90 and are arranged to extend with the "throw" of one crank in alignment with the "throw" of the other crank. The cranks 94 and hubs 95 are provided with a central bore to accommodate a bolt or the like 96 by which the cranks and the shaft 90 are held in assembled relationship. The cranks 94 rotate in parallel horizontal planes above and below the housing 52 and are provided with suitable bearing seats for anti-friction bearings 100. The anti-friction bearings 100 have their axes in vertical alignment and eccentric to the axis of the shaft 90 and the hubs 95. The anti-friction bearings 100 rotatably connect the cranks 94 to intermediate portions of a pair of arms 102 and 103, to be described later. Dust seals 104, of suitable design, are arranged between the cranks 94 and the arms 102 and 103. The dust seals are circular and extend concentrically about the anti-friction bearings 100 at such radius as to encompass the ends of the bolt 96. The bearings 100 are thus sealed against the entry of dust, grit and the like. Additional dust seals 101 are arranged between the cranks 94 and the housing 52 to protect the bearings 88 and 89 and the gears within the housing.

Referring now to Figs. 4 and 6, the arms 102 and 103 extend generally forwardly from their connection with the cranks 94 and are attached, at their forward ends, to an undercutter head 110. The arms 102 and 103 may be bolted or otherwise securely fastened to the head 110 at the top and bottom thereof. As clearly evident from Fig. 6, the uppermost surfaces of the arms 102 are substantially flush with the uppermost surface of the head 110 which latter surface is substantially coplanar with the upper surface of the plate 60 heretofore described. The portion of the arm 102 extending rearwardly from the head 110 is below the upper surface of the plate 60 a sufficient distance to pass under the plate with suitable working clearance therebetween. In like manner, the lowermost surface of the arm 103 is spaced slightly above the bottom surface of the plate 24.

The undercutter head 110 is of considerable lateral extent, transversely of the machine and is formed with a plurality of forwardly projecting portions 111, 112 and 113. Each of the projecting portions is provided with a plurality of sockets 114 adapted to receive the shanks 115 of suitable pick points.

The picks are arranged in a plurality of groups 116, 117 and 118. Suitable set screws 120 may be arranged to clamp the pick points in their respective sockets. The pick points in each group are arranged with their tips lying in the same vertical plane, but the uppermost and lowermost pick points are spaced outwardly of the points nearer the vertically central portion of the undercutter head. Thus, the pick points of each group are arranged in V formation with the apex of the formation pointed inwardly toward the center of the machine. By this arrange-

ment the center point of each group makes a first cut and the other points of that group are enabled to cut mineral material into the groove formed by the leading pick. The action is in the nature of "undercutting" the material for each succeeding pick point. As evident from Figs. 6 and 7, the axes of the pick points diverge forwardly in a vertical plane whereby the tips of the uppermost and lowermost picks are located respectively above and below the top and bottom surfaces of the heads 110. By this arrangement the picks cut a kerf having a vertical dimension somewhat greater than that of the head 110 and sufficient for the spaced plates 24 and 60 to enter the kerf with suitable working clearances.

The arms 102 and 103 extend rearwardly beyond their connection to the cranks 94 (see Fig. 6) and terminate at their rear ends in aligned hubs 122 directed inwardly toward each other and abutting at their innermost ends. The hubs 122 provide seats for the inner races of the anti-friction bearings 124. The hubs 122 are also provided with aligned axial openings adapted to receive a tie bolt or the like 126.

Now referring to Fig. 4, the rearwardly extending arm 55 of the housing 52 is provided, intermediate its ends, with suitable seats for anti-friction bearings 128 (see Fig. 8). The anti-friction bearings 128 rotatably support aligned hubs 130 carried by upper and lower sections 131 and 132, respectively, of a guide link 133. The upper and lower sections of the guide link 133 are held in assembled relationship along the axis of the bearings 128 by means of a tie bolt 134, or other suitable means. As clearly apparent from Fig. 8, the guide link 133 extends generally inwardly of the machine toward the center line thereof and is of less vertical extent at its innermost end whereby the said end may be received between the rearmost end portions of the arms 102 and 103. The upper and lower sections of the link 133 are provided, at the said innermost ends, with suitable seats for the anti-friction bearings 124, previously described as being at rearmost ends of the arms 102 and 103. If desired, additional bolts or cap screws such as shown at 140 may be employed to further assist in holding the sections 131 and 132 in assembled relation. Suitable dust seals 141 are arranged between the arms 102 and 103 and the link 133 and similar dust seals are provided between the other end of the link 133 and the portion 55 of the housing 52.

Throughout the disclosure thus far all rotary shafts or links have been shown or described as being mounted in anti-friction bearings of the "ball bearing" type; however, it is to be understood that other suitable bearings may be employed with equal facility and the invention is not to be limited to the use of ball bearings. For instance, bronze or other sleeve bearings may be employed or suitable "roller" type bearings may be used.

From the description thus far, it will be clear that rotation of the shaft 76, by chain 24, will cause the cranks 94 to rotate about their vertical axis and drive the intermediate portions of the arms 102 and 103 in a horizontal circular path. The link 133 guides the rearmost ends of the arms 102 and 103 in an arcuate path extending generally in a fore and aft direction relative to the machine. The movements of the intermediate and rearmost portions of the arms just described result in an orbital movement of the head 110 and the pick points carried thereby with the

5 pick points always extending generally forwardly. The orbital movement of the central or foremost pick point of each group is indicated by dotted lines in Fig. 5.

10 The spacing between the groups of pick points is so chosen that the orbital path of the pick points in the foremost group 116 overlaps the orbital path of the pick points in the intermediate group 117, which path in turn overlaps that of the rearmost group 118. During operation of the machine the shaft 76 will be rotated in such direction that the pick points move about their orbital paths in the directions indicated by the arrows in Fig. 5 and it will be evident that the 15 points will be in engagement with the material being mined during their movement inwardly toward the longitudinal center line of the machine. During such inward movement each group of pick points will loosen a certain amount of mineral material and move the same inwardly until those points have reached the inner limit of their movement. Such a body of material is 20 represented at 150 in Fig. 5 of the drawings and it will be seen that the configuration of the head 110 is such that the body of material 150 is positioned substantially entirely within the orbital path of the foremost group of pick points 116. As the cranks 94 continue to rotate, all of the 25 picks will be moved rearwardly away from the mineral material and outwardly to start a new cut. During the outward and forward movement of the picks of the group 116, those picks will move around the body of material 150 and will engage the mineral face outwardly of that 30 body of material, thus each cycle of operation of the groups 116 and 117 results in those groups engaging the body of material loosened by the next outward group and moving that body of material inwardly toward the center line of the 35 machine and somewhat rearwardly therealong. In other words, all of the material loosened by each group of pick points 117 and 118 in one cycle of operation is engaged and moved by the 40 next inward group in the next cycle of operation and all of that material will be moved inwardly 45 of the machine.

As clearly shown in Fig. 5, the innermost pick 50 of the outer group 118 moves along an orbital path extending laterally beyond the lateral extremity of the machine frame, thereby insuring a kerf 55 of sufficient width to accommodate the forwardly extending frame portion of the machine. It is also to be noted that the head 110 is of such configuration that it extends across the foremost end of the housing 46 when in the position shown in Fig. 3.

Referring now to Fig. 4, the head 110 is shown 60 as having a bracket 152 bolted or otherwise fastened to its laterally innermost end, said bracket extending inwardly toward the center line of the machine and carrying a vertical pin 154 defining a vertical pivot axis. The pin 154 extends vertically from a position adjacent the bottom of the machine (see Fig. 7) to a position approximately even with the bottom of the attachment portion 63 of the casing 52. The portion of the bracket 152 which supports the pin 154 may be 65 in the form of a pair of spaced ears 156. The pin 154 pivotally mounts the front end of a pusher plate 158, which has a plurality of ears 159 in alignment with the ears 156 of the bracket 152 and through which the pin 154 extends. The 70 pusher plate 158 is of a sectional configuration as shown in Fig. 9 and extends rearwardly and outwardly from the pin 154 into telescopic sliding

engagement with a second pivoted plate 160. The plate 163 may be provided with suitable guide means 162 engaging with complementary edge portions of the plate 158 to define a telescopic structure pivoted at one end to the movable cutter head 110. The plate 160 is pivoted at its rearmost end to the main frame of the machine adjacent the foremost edge 47 of the bottom plate 24 on a vertical pin 163. The pivot pin 162 may be supported by suitable bosses 164 and 165 carried by the plates 68 and 24 respectively (Fig. 7). As clearly evident from Figs. 4 and 7, the pusher mechanism comprising plates 158 and 160 is so related to the head 110 and the frame plate 50 as to define a movable wall substantially impervious to the passage of mineral material at the pivot portions thereof. Thus the bracket 152, the plates 158 and 160, and the frame plate 50 define one side of a passageway extending from the forward portion of the undercut kerf rearwardly to a position adjacent the forward end of the central conveyor previously described. The bottom surface of the passageway is defined by the floor of the mine and the top of the passageway is partially closed by the plates 68 and 69. The plate 68, as previously described, does not close the top of this passageway all the way back to the central conveyor, but terminates short thereof to provide an upwardly extending opening at the rear end and through the top of the passageway right adjacent the upwardly movable portions of the central conveyor. It will be evident that the cut material removed from the mineral face by the picks 116, 117 and 118 will be cyclically moved inwardly to a position adjacent the front surface of the bracket 152 and upon the following cycle of operation the bracket 152 will move rearwardly and outwardly from such material to a position where the inner face of the plate 158 will engage that material and move it inwardly and rearwardly during the cycles of movement illustrated in Figs. 3, 4 and 5. As successive bodies of material, as shown at 150 (Fig. 5), are moved inwardly by the picks and rearwardly by the plates 158 and 160, a large mass of cut material will be accumulated in the described passageway and forwardly of the central conveyor. When this large mass of material reaches such a volume as to substantially fill the passageway, successive cycles of operation of the pusher plates 158 and 160 will force the entire mass rearwardly and snugly against the central conveyor whereby upwardly moving flights 32 of said conveyor will engage and carry portions of the mineral material upwardly through the space between said conveyor and the rear edge of the plate 68 to the upper surface of the top plates 26 whence it will be moved rearwardly of the machine along with the material broken down from the vertical face of the material by the picks 13 and 14. This movement of material will be assisted and insured by forward movement of the entire machine, since the cut material in the passageway rests upon the floor of the mine.

If desired, flexible sealing means of any suitable type may be arranged between the top edges of the plates 158 and 160 and the bottom of the plate 68 and/or from the brackets 152 to upper arm 182. Such means have not been illustrated in the drawings since they may take many various forms.

The operations described in connection with the undercutting head shown in Figs. 3-5 are identical to the operations performed by the undercutting head on the opposite side of the ma-

chine except that those operations are in a reverse direction; however, they still take place in a direction inwardly toward the center line of the machine which lies between the two cutter heads. As also shown in Fig. 5 of the drawings, the orbital path of movement of the innermost pick of the group 116 extends, at its inner end, across the longitudinal center line of the machine and crosses that center line at points indicated at A and B. Since the machine is constructed symmetrically and the opposite cutter head, shown in dotted lines at C, is constructed to move in an exactly similar path, its innermost pick point will also cross the center line 15 of the machine at the points A and B, thus insuring a continuously cut kerf extending entirely across the working face of the mineral being mined. The cyclical operations of the two cutter heads are, however, not in exact unison 20 since they would then arrive at point A simultaneously and each would then interfere with the movement of the other. To prevent such interference, the movements of the two heads are so timed that the innermost picks of one head, as shown in full lines in Fig. 5, will pass the point A substantially in advance of the time the innermost points of the other head reach point A. The dotted line fragmentary showing of the other pick head in Fig. 5 indicates generally the relationship between the two heads as they approach the innermost points of their orbital paths, and as clearly shown, one head completes its cutting movement somewhat in advance of the other. Since the two cutter heads are driven by sprocket chains and gears from a common shaft (30) the timed relation just described will be maintained for all cycles of operation. The two heads are preferably so timed as to be as nearly in synchronism as possible so that lateral reactions, on the machine, due to the cutting forces involved, will be largely neutralized since the reactions resulting from the movements of the two heads are in opposite directions.

It has been found in actual operation that the two cutter heads need not be out of synchronism with each other but may move through their cycles of operation in exact synchronism when arranged so that the innermost picks on each head do not move in a path overlapping the path of the innermost picks on the opposed head. It has been found that all of the mineral material will be removed from the kerf if the paths of the innermost picks are just short of tangency at their innermost ends. Such an arrangement is contemplated by the present invention and has the advantages of enabling the two cutter heads to be moved in synchronism, thus balancing the lateral forces acting on the machine at all times.

Reference has previously been made to auxiliary or apron conveyors 35 (see Figs. 2, 6, 7 and 11). As previously described, the apron conveyors 35 are trained over pairs of sprockets 34 carried by the shaft 30. A second shaft 168 is carried by the main frame of the machine rearwardly of the shaft 30 but parallel thereto and is suitably journalled, in bearings (not shown) for free rotation about its axis. The shaft 168 carries pairs of sprockets 170 in alignment with the sprockets 34 on the shaft 30 and the endless conveyors 35 are trained over the sprockets 170 and then back to the sprockets 34. Figure 2 shows a single shaft 168 extending across the entire machine, but clearly two

short aligned shafts could be employed, each being just long enough to accommodate the sprockets 170.

Figs. 6 and 11 show the construction of the individual links of the conveyor 35 which comprises a transverse outer plate portion 172, a pair of rearwardly extending ears 174 at the ends of the link and forwardly extending ears 176 somewhat inwardly of the ears 174. The forwardly extending ears of each link extend between the ears 174 of the next adjacent link and all ears are provided with aligned openings 178 to receive transverse pins 180. The pins 180 are effective to pivot adjacent links together and also constitute the means engageable between the teeth of the sprockets 34 and 170 to effect driving and guiding of the conveyors 35. Fig. 6 further illustrates the construction of the outer plate portions 172 which have forwardly and inwardly curved edges 182. The curved edges 182 have an outer surface concentric to the axis of the pin 180 so that the entire conveyor may be flexed around the sprockets while maintaining a continuous outer surface substantially impervious to fine material.

The dimensions of the links of the apron conveyors 35 are such that an exact multiple thereof will extend from the end of one central conveyor flight 32 to the next conveyor flight and the entire length of the conveyor 35 is a multiple of the distance between successive flights 32 of the main conveyor. Certain of the pins 180 are of a length greater than that of the individual conveyor links and extend inwardly a substantial distance as shown at 184 in Figs. 2 and 11. The distance between successive projecting pins 184 is equal to the distance between flights 32 on the central conveyor and they are so related that during movement across the top of the plate 26, in which the conveyors 35 and the central conveyor move in unison, the portions 184 extend inwardly immediately adjacent the rear edges of the ends of the conveyor flights 32. Since the conveyor flights 32 are pivoted to the main chain 28, the portions 184 will be effective to prevent such pivotal movement during the time the conveyors are moving as a unit at the forward portion of the machine. Thus, masses of material moved from one of the conveyors 35 to the central conveyor will not be able to tilt the near end of the flight 32 rearwardly and destroy the conveying function of the central conveyor. As also shown in Fig. 7, the auxiliary or apron conveyors 35 define an upper surface substantially parallel to, but above, the upper surface of the plate 26.

Although a specific type of auxiliary or apron conveyor has been described and shown, it is to be understood that other forms may be employed with equal facility. For instance, it has been found that a screw conveyor extending rearwardly from the shaft 30 may be employed with equal facility and such a conveyor is contemplated within the scope of the present invention. A screw conveyor of this type was readily arranged to be driven, by suitable gearing at its forward end, from the shaft 30 previously described.

The breaking down mechanism comprising the arms 12 and pick points 13 and 14 includes a plurality of the elements shown in Fig. 1 extending completely across the width of the machine to break down mineral material across a face having a lateral dimension substantially equal to the width of the kerf cut by the undercutting mecha-

nism previously described. It will thus be seen that much of the material broken down by the picks 13 and 14 will fall near the lateral extremities of the machine onto the plate 26 and the apron conveyors 35. As the apron conveyors 35 move rearwardly, such material will be carried toward the rear of the machine thereby. It is contemplated that stationary sweep plates 190 be fixedly attached to the machine frame and extend angularly across the apron conveyors 35 to force material carried thereby inwardly toward the central conveyor so that all such material will be transferred to the central conveyor before it reaches the rearmost end of the top flight of conveyor 35. Thus, all material broken down will be delivered to the main or central conveyor to be moved to the rear of the machine. Since the apron conveyors do not extend outwardly to the lateral extremities of the machine, it is also contemplated that suitable upwardly and outwardly extending guide plates or the like be provided to catch material that would otherwise fall outside the sweep plates 190 and direct such material to the inside thereof. Such means are not shown in the drawings since they may assume various shapes and configurations not germane to the present invention.

The power for driving the conveyors and undercutting mechanism described herein may be supplied in any suitable or convenient manner. For instance, sprocket chains 195 and 196 (Fig. 2) may extend from sprockets on the shaft 30 rearwardly through the machine frame to a suitable motor or motors. By this arrangement power will be applied to the shaft 30 which in turn will drive the conveyors and the chains 34 extending forwardly to the undercutting heads. As an alternative, power may be supplied to the shaft 30 directly through the main conveyor chain 28 since such chain must necessarily pass over a suitable sprocket wheel somewhere at the rear of the machine. Power may be applied directly from the motor to such sprocket wheel or supporting shaft therefor.

Although a single specific embodiment of the invention has been shown and described, it will be apparent that many modifications may be made in the various elements without departing from the scope of the invention. For instance, an inwardly extending cleat or cleats may be attached to the forward pusher plate 153 to further assist in pushing undercut material rearwardly toward the central conveyor. It is understood that the invention is not to be limited to the specific embodiment shown and described, but may be practiced by modifications falling within the scope of the appended claims.

I claim:

1. In a mining machine, a forwardly directed undercutter mechanism comprising, a head member, means for moving said head member along an orbital path in a generally horizontal plane, said path extending from a lateral extremity of said machine inwardly toward the longitudinal centerline thereof then rearwardly then outwardly and forwardly, a plurality of forwardly and inwardly directed pick means carried by said head, said pick means being arranged in groups of closely adjacent but vertically spaced picks, said groups being spaced apart in a direction generally parallel to the forward portion of said orbital path, the transverse dimension of said orbital path being at least equal to the spacing 75 between adjacent groups of pick means.

2. In a mining machine, a forwardly directed undercutter mechanism comprising, a head member, means for moving said head member along an orbital path in a generally horizontal plane, said path extending from a lateral extremity of said machine inwardly toward the longitudinal centerline thereof then rearwardly then outwardly and forwardly, a plurality of forwardly directed pick means carried by said head, said pick means being arranged in groups, spaced apart in a direction generally parallel to the forward portion of said orbital path, the transverse dimension of said orbital path being at least equal to the spacing between adjacent groups of pick means, said head member including a rearwardly extending portion, said first means including crank means drivingly engaging said rearwardly extending portion intermediate the ends thereof to move a portion of said rearwardly extending portion around a circular path, and a laterally extending link pivoted to said rearwardly extending portion rearwardly of said crank means and to a fixed pivot.

3. In a mining machine, a forwardly directed undercutter mechanism comprising, a head member, means for moving said head member along an orbital path having a portion adjacent the longitudinal center line of said machine extending inwardly toward said center line and rearwardly, forwardly directed pick means carried by said head, and pusher means pivoted to the innermost side of said head and extending rearwardly to a fixed pivot.

4. A machine as set forth in claim 3 wherein said pusher means comprises a forward vertically extending plate element pivoted to said head member on a vertical axis and a rear vertically extending plate element telescopically engaging said forward plate element and pivoted at its rearmost end on a vertical axis at said fixed pivot.

5. A machine as set forth in claim 3 having a pair of said orbitally movable heads at opposite sides thereof and in which the said fixed pivots are laterally spaced apart, and rearwardly movable conveyor means arranged to receive material moved rearwardly between said fixed pivots.

6. In a mining machine, an undercutting mechanism at the forward end thereof comprising, a frame, a movable head having forwardly extending pick means thereon, vertically spaced arms carried by said head and extending rearwardly therefrom, a housing carried by said frame between said rearwardly extending arms, a pair of vertically spaced cranks rotatably carried by said housing on vertically opposite sides thereof, each of said cranks being pivoted to an adjacent arm intermediate the ends thereof, and means guiding the rearmost ends of said arms along a generally fore and aft path.

7. A machine as defined in claim 6 wherein the said means for guiding the rearmost ends of said arms comprises a laterally extending link pivoted at one end to the ends of said arms and pivoted at its other end on an axis fixed relative to said housing.

8. A machine as defined in claim 6 wherein the said housing is fixedly mounted on one side of a forwardly extending hollow frame member, and drive means extending within said hollow frame member and into said housing to drive said cranks.

9. In a mining machine, a frame having elongated forwardly extending portions constitut-

ing the forward end and the lateral extremities of said frame, an undercutting means carried by each of said extending portions on the inner side thereof, said undercutting means being arranged 5 to cut a continuous kerf extending laterally beyond said forwardly extending portions, and plate means extending across the tops of said forwardly extending portions and adapted to enter the said kerf and bear against the upper surface 10 thereof, said undercutting means being orbitally movable in a horizontal plane to cut material being mined and move said material toward the longitudinal center line of said machine, pusher means driven by said undercutting means to engage said material moved by said undercutting means and move the same inwardly and rearwardly of said machine below said plate means, and conveyor means arranged to receive material moved by said pusher means.

20 10. In a mining machine, a frame having a forward portion adapted to enter a kerf in mineral material, said forward portion including a substantially horizontal plate extending completely transversely across said machine and defining the 25 uppermost portion of said forward portion, said plate being adapted to engage the downwardly facing surface of said kerf and having a rear terminal edge extending transversely of and substantially completely across said machine, break-down means carried by said frame and cyclically movable downwardly to a position closely adjacent but slightly rearwardly of said terminal edge whereby to break down mineral material above said kerf which overhangs said terminal edge.

30 11. In a mining machine, a frame having a forward portion adapted to enter a kerf in mineral material, said forward portion including a substantially horizontal plate extending completely transversely across said machine and defining the 35 uppermost portion of said forward portion, said plate being adapted to engage the downwardly facing surface of said kerf and having a rear terminal edge extending transversely of and substantially completely across said machine, break-down means carried by said frame and cyclically movable downwardly to a position closely adjacent but slightly rearwardly of said terminal edge whereby to break down mineral material above said kerf which overhangs said terminal edge.

40 12. In a mining machine, a frame having a forward portion adapted to enter a kerf in mineral material, said forward portion including a substantially horizontal plate extending completely transversely across said machine and defining the uppermost portion of said forward portion, said plate being adapted to engage the downwardly facing surface of said kerf and having a rear terminal edge extending transversely of and substantially completely across said machine, break-down means carried by said frame and cyclically movable downwardly to a position closely adjacent but slightly rearwardly of said terminal edge whereby to break down mineral material above said kerf which overhangs said terminal edge, and a second substantially horizontal plate carried by said frame below said first plate and extending rearwardly from said terminal edge and continuously across said machine in a transverse direction.

45 13. In a mining machine, a frame having laterally spaced forwardly extending portions, a plate extending across the tops of said portions and attached thereto, a housing carried by each extending portion on the inner side thereof and attached thereto at longitudinally spaced points, each housing being attached to said plate at a point spaced substantially inwardly of said extending portions of said frame, movable undercutting picks, said picks being mounted on and driven by means carried by said housings.

50 14. In a mining machine, a forwardly extending transverse plate spaced above the bottom of said machine and having a rear terminal edge, an endless conveyor extending longitudinally of said machine and mounted for movement along a path extending forwardly adjacent the bottom of said machine then upwardly slightly to the rear of said terminal edge then rearwardly, undercutting means carried by said machine below and forwardly of said plate, and means below said plate

for guiding and moving material to the upwardly moving portion of said conveyor.

14. A machine as defined in claim 13 wherein said last-named means comprises laterally spaced vertical side walls defining a passageway therebetween, opposed portions of said side walls being pivoted on vertical axes, and means for cyclically swinging said portions about said axes in an inwardly and rearwardly direction to move material therebetween toward said conveyor.
